UNITED STATES PATENT OFFICE.

ALFRED H. HAAG, OF BALTIMORE, MARYLAND, ASSIGNOR OF FIFTEEN ONE-HUNDREDTHS TO E. HAYWARD FAIRBANKS, OF MERCHANTVILLE, NEW JERSEY.

LOUD SPEAKER FOR RADIO RECEIVING APPARATUS.

Application filed January 28, 1925. Serial No. 4,708.

In loud speakers for radio receiving apparatus of the character commonly in vogue, it is customary for the horn or amplifying element either to stand exposed upon a base, 5 within which is the unit, or the amplifier is contained in a rectangular box like casing, which is generally superimposed upon the radio cabinet giving the appearance of rectangular boxes piled on each other. In the 10 first mentioned construction where the amplifier is exposed and its lower portion of gradually reduced area tapering downwardly towards the base there is a slight impairment of the reproductions owing to 15 the vibrations of the amplifier body when in use which in practice should have both its ends retained in a substantially fixed position to attain the best results.

In addition the mouth or exit end of this 20 class of amplifiers being relatively large and heavy as compared with the lower amplifier portion connected to the base or unit, there is a substantial weight at the upper portion of the device, which tends to vibrate more or 25 less according to the character of the reproduced sounds, and such vibration is but partially resisted or counteracted by the lower goose neck reduced portion of the device as the lowermost portion of the 30 device is of the least area in cross section. In the second "square box" class of devices, the entire inner capacity or area of the box or casing has not heretofore been utilized to the maximum extent to which I 35 utilize it, by giving the amplifier the length and contour which I have devised, and there is consequently lacking the maximum amount of amplification, which I attain in my present novel construction.

40 In order to avoid the objectionable features and defects of these prior devices, I have devised the present construction, which results in an outer casing of a pleasing and graceful contour, and wherein a maximum amplification is obtained. In addition as it is desirable to have a time piece in proximity to the radio apparatus, so that the operator can readily ascertain from his radio log the exact time of the operation of the 45 various broadcasting stations, so that the desired station can be instantly tuned in, I provide the amplifier exit with a foraminous covering, of silk, fine wire mesh or other suitable material having a clock face 50 portrayed, stamped or otherwise impressed

thereon, so that the operator, without leaving or glancing from his radio can ascertain from a glance at the loud speaker the exact time, and tune in his desired station accordingly, the loud speaker casing being utilized 60 as a support for the clock mechanism and the amplifier and its adjuncts, being utilized for a bearing for the clock arbor or mechanism which actuates the clock hands.

By this novel construction, in a single 65 structure, I have produced a highly efficient sound amplifier whose casing is further utilized not only to support and conceal the amplifier and its adjuncts and to hold them properly in position, but also to support a 70 suitable clock mechanism, whose clock face consists of a foraminous dial, which not only affords no obstruction to the exit of the reproduced sound waves, but also serves as 75 an ornamental and efficient time indicator. 80

To the above ends my invention consists of a novel construction of a loud speaker for radio receiving apparatus, wherein the casing or outer portion thereof is given a contour that results in a graceful, ornamental and pleasing appearance, simulating a clock case or the like, said casing being constructed in a novel manner and if desired built up of sections, which can be cheaply made in large quantities in duplicate, and provision is made for utilizing to a maximum extent the internal capacity or area of the casing, which has heretofore been wasted, for housing and supporting an amplifier of maximum length, which has the 85 loud speaker unit connected to its rear end and supported in the rear casing wall, while the front or exit end of the amplifier is mounted in the front wall of the casing and secured thereto and the joint therebetween concealed in a novel manner.

It further consists of a novel construction of loud speaker of the character hereinabove referred to, wherein the front exit portion thereof is covered with suitable material, 100 having thereon a clock face or dial, provision being made for housing within the same casing which contains the amplifier, suitable clock actuating mechanism; a wall of said amplifier serving as a bearing for 105 the clock arbor.

It further consists of a novel construction of loud speaker casing, having its front and rear walls in duplicate, the rear end of the amplifier carrying the loud speaker unit 110

being supported in the rear wall and the front end of the amplifier being supported in the front wall of the casing, in combination with an outer ring, secured to the casing
 5 front which serves to conceal the exit end of the amplifier and to also retain in position the silk or wire mesh or other material which covers the exit opening of the amplifier, and may if desired be utilized as a clock face.
 10 It further consists of other novel features of construction and advantage, all as will be hereinafter fully set forth and pointed out in the claims appended hereto.

For the purpose of illustrating my invention I have shown in the accompanying drawings forms thereof which are at present preferred by me, since they have been found in practice to give satisfactory and reliable results, although it is to be understood that
 15 the various instrumentalities of which my invention consists can be variously arranged and organized and that my invention is not limited to the precise arrangement and organization of these instrumentalities as here-
 20 in shown and described.
 25

Fig. 1 represents a perspective front view of a loud speaker for radio receiving apparatus, embodying my invention.

Fig. 2 represents a horizontal section on line 2—2, Fig. 3, showing the contour of the amplifier, certain parts of the amplifier being shown in elevation.

Fig. 3 represents a vertical section on line 3—3, Fig. 1.

Fig. 4 represents on an enlarged scale, a horizontal section on line 4—4, Fig. 1.

Figs. 5 and 6 represent vertical sectional views of modifications showing the casing as made of metal.

Fig. 7 represents a perspective view of my invention applied to a grandfather's clock.

Fig. 8 represents a section on line 8—8, Fig. 7.

Figs. 9 and 10 represent front elevations of clock dials.

Similar numerals of reference indicate corresponding parts.

Referring to the drawings:—

1 designates my novel construction of loud speaker, the same comprising a front wall 2 and rear wall 3, said walls being made in duplicate and attached to or supported on a suitable base 4. The front and rear walls are provided with a convex upper portion, as indicated at 5, and concave side portions as indicated at 6, said side portions merging into and abutting against the lower convex or moulded transverse terminal portions or bars 7, whereby a very graceful and pleasing contour is given to said walls, the latter simulating a clock case. The front wall 2 has a circular opening 8 therein, in which is contained the exit portion 9, of the amplifier 10, whose construction and contour will be understood from Figs. 2 and 3. The

smaller or inlet end of the amplifier is indicated at 11, at which point, the loud speaker unit 12, is attached, said unit being seated or positioned in the seat or hole 13 in the rear wall 3, as will be understood from Fig. 2. The amplifier is composed of the gradually widened conical member 14, which is reversely bent upon itself as indicated at 15, and then again reversely bent and continued forwardly as indicated at 16, which portion 16 merges into the main body 17 and exit end 9, which is seated and secured within the circular opening 8 by screws or the like.

It will be evident from Figs. 1 and 2, that the amplifier, composed of the portions 14, 15 and 16 and the intervening portions, which are of gradually increasing area in cross section from the inlet 11 to the exit 9, is of a maximum length, since I provide the return bend or loop construction comprising the portions 14, 15 and 16 whereby a maximum amplification is attained. Over the exit end 9 of the amplifier I place the disk or covering of silk or fine wire mesh, as indicated at 18, and said mesh is secured in position by the outer ring 19 which is held in position by screws or other fastening devices 20. The space between the front and rear walls 2 and 3 is occupied by the wall 21, which may be of metal or fibre or veneering of any suitable ply, which conforms to the general contour of said front and rear walls 2 and 3, the edges of said veneering being rabbeted into said walls 2 and 3, as indicated at the points 22 and 23.

In my novel construction, I am enabled to utilize the wire mesh or other material, 18 as a clock face or clock dial, by placing thereon, numerals as 24. The rear inclined wall 25 of the amplifier has the horizontal bearing 26 formed therein for the clock arbor 27, which carries the clock hands 28 and 29, said arbor being operated by suitable conventional clock mechanism contained in the casing 30, which is mounted in the rear casing wall 3. The front end of the clock arbor 27 may pass through and be guided in a bearing in the center of the bar 31, which preferably extends horizontally across the exit end 9 of the amplifier in the rear of the ring 19, and has its ends secured against the front of the wall 2 by the screws 20 already described as securing said ring 19 in position. I preferably make the rear wall 3 solid, but if desired I may split the front wall 2, at the upper and lower points, 32 and 33, which facilitates the assembling of the front end 9 of the amplifier in position, said front end terminating about flush with the front wall 2 as seen in Fig. 3. Following the assembly of the amplifier the disk 18 is next placed in position, and when the ring 19 is assembled, and secured in position it conceals the edge of the disk or clock face

18, and also conceals the front end of the amplifier, thereby giving a neat and attractive appearance to the entire front of the loud speaker casing.

5 In the above described construction, the clock mechanism can of course be omitted, if desired, in which case the disk 18 would be plain with the numerals 24 omitted, and the parts 26, 27, 28, 29, 30 and 31 would

10 also be omitted.

It is obvious that a loud speaker, constructed as seen in Fig. 1, either with or without the clock mechanism presents a very attractive appearance as compared with the 15 top-heavy exposed horns, or the rectangular box like structures now in vogue, and in addition marked acoustical advantages are gained, by anchoring the front and rear ends of the amplifier, and by increasing the 20 amplifier area for the maximum amplification of the sound waves, in the manner explained. If desired the loud speaker casing can be made entirely of sheet metal as seen in Figs. 5 and 6, the casing in Figs. 5 and 6

25 which it will be understood are horizontal sections conforming generally to Fig. 2. In Fig. 5, 33 designates the casing front and 34 its rear having the central seat 35 for the clock casing 30, the outer shell being indicated at 36 and spot welded at the points

37.

In Fig. 6, 38 and 39 represent the front and rear walls and 40 the outer wall, the contiguous edges being joined by pressed seams 35 as indicated at 41, it being understood that the front appearance of the casings seen in Figs. 5 and 6 conforms to Fig. 1.

In Figs. 7 and 8, I have shown the broad principle of my invention as applied to a "grandfather's or hall clock" cabinet 42, the radio being indicated at 43, which is accessible by the drop door 44, the radio being supported on the partition 45, which may also support the unit 46, leading to the amplifier 47. The manner of securing the clock dial and its adjuncts in position is the same as already described, and will be understood without further description.

In the construction seen in Figs. 7 and 8 I have designated the clock mechanism and its adjuncts with the same reference letters as already used and it will be apparent that a grandfather's clock or hall clock of the construction described, is especially adapted for the utilization of my invention, since there is a great deal of wasted space within the cabinet of the same.

In my invention, the intermediate portion of the cabinet is readily adapted to receive the radio, while the lower portion of the cabinet is especially adapted to receive the A and B batteries, as indicated at 48 and 49, said batteries being supported upon the 65 partition or shelf 50, and being readily

accessible through the front door or panel 51, or the rear wall 52, either or both of which can obviously be made removable or movable if desired.

It will be apparent, that if desired I may 70 place the figures for the clock dial directly upon the ring 19 as seen in Figure 10 and if desired I may entirely omit the foraminous cover or disc 18 in which case the parts will appear as seen in Figure 10, in which case 75 the front of the clock or the clock dial will appear as seen in Figure 10, the hands of the clock and the clock arbor being omitted from said figure.

By positioning the clock and its adjuncts, and collocating the clock dial, in proximity to the amplifier exit, the radio operator is enabled to ascertain readily and exactly, while or before he is tuning in, the exact 80 time of the broadcasting of the desired 85 performance, as is evident.

Having thus described my invention what I claim as new and desire to secure by Letters Patent, is:—

1. In a device of the character stated, an 90 amplifier for sound reproducing mechanism having a clock face formed on the front of the vibratory portion thereof and movable clock hands coacting with said clock face.

2. As a new article of manufacture, a 100 cover for the exit opening of an amplifier for sound reproducing mechanism comprising a sheet having a clock dial and movable clock hands coacting with said sheet positioned in proximity to the outer periphery thereof.

3. As a new article of manufacture, a disk 105 having a clock face thereon and adapted to serve as a cover for the exit opening of an amplifier for sound reproducing mechanism, movable clock hands coacting with said face and a ring inclosing said cover and concealing the peripheral edges of said disk and amplifier.

4. The combination of a sound amplifier, a casing therefor having a front opening aligning with the exit end of said amplifier, a foraminous sheet covering said opening 115 movable clock hands on said sheet, and an outer ring secured to said casing and concealing the edges of said sheet and amplifier.

5. In a loud speaker, an amplifier, a casing therefor having a front portion in which the exit end of said amplifier is secured, 120 a sheet of foraminous material having a clock dial thereon positioned on the front of said casing to conceal the exit portion of said amplifier, movable clock hands coacting with said dial and a ring covering the 125 outer edges of said sheet and amplifier and secured to the front of said casing.

6. In a device of the character stated, an 130 amplifier, a casing therefor, having a front wall in which the exit end of said amplifier

is fixedly secured, a sheet of foraminous material having a clock dial thereon secured to said front wall to conceal the amplifier exit, movable clock hands coacting with 5 said dial and a ring surrounding and concealing the periphery of said sheet and the junction of said amplifier with said front wall.

7. The combination of an amplifier casting formed of front and rear vertical walls having a convex top, convex side portions and transverse end pieces convex at their tops, said front wall having a circular exit opening therein, a top wall convex at its 10 top and concaved at its sides and secured in inner juxtaposed grooves in said front and rear walls, said grooves being convex 15

at their tops and merging into convex side grooves, and an amplifier contained in said casing and having its exit portion secured 20 in said circular opening in said front wall.

8. In a loud speaker, an amplifier having the inlet 11 and the substantially horizontally disposed inlet branch 14 bent upon itself at 15 and having the branch therefrom 25 bent at 16 to form the main amplifier body 17 having the exit 9, in combination with a casing having a convex top portion conforming to the outer portion of said amplifier, and concave side portions, the inlet 30 portions of said amplifier being contained within and below said concave side portion.

ALFRED H. HAAG,

CERTIFICATE OF CORRECTION.

Patent No. 1,684,956.

Granted September 18, 1928, to

ALFRED H. HAAG.

It is hereby certified that error appears in the printed specification of the above numbered patent requiring correction as follows: Page 3, lines 100 to 102, claim 2, strike out the words "positioned in proximity to the outer periphery thereof," and insert the same to follow after the word "dial" in line 99; and that the said Letters Patent should be read with this correction therein that the same may conform to the record of the case in the Patent Office.

Signed and sealed this 20th day of November, A. D. 1928.

(Seal)

M. J. Moore,
Acting Commissioner of Patents.
